UNITED STATES PATENT OFFICE.

MONROE M. SCHWARZSCHILD AND BELLE SCHEUER, OF NEW YORK, N. Y.

TYPE-WRITING DOLL TOY.

1,153,524.

Specification of Letters Patent. Patented Sept. 14, 1915.

Application filed June 29, 1915. Serial No. 36,944.

To all whom it may concern:

Be it known that we, MONROE M. SCHWARZSCHILD and BELLE SCHEUER, both citizens of the United States, residing at New York, 5 in the county of New York and State of New York, have invented certain new and useful Improvements in Type-Writing Doll Toys; and we do hereby declare the following to be a full, clear, and exact description 10 of the invention, such as will enable others skilled in the art to which it appertains to make and use the same.

Our invention consists in the novel features hereinafter described, reference being 15 had to the accompanying drawings which illustrate one embodiment of the invention selected by us for purposes of illustration, and said invention is fully disclosed in the following description and claims.

20 Referring to the drawings: Figure 1 represents a perspective view of an embodiment of our invention comprising the typewriting doll toy complete, with the doll or figure supported in operative relation with the other parts of the apparatus. Fig. 2 represents a vertical sectional view through the toy. Fig. 2^a is a detail perspective view of a clip which we conveniently employ for connecting the movable arms of the doll or 25 figure to the arm operating devices. Fig. 3 is a horizontal sectional view of the apparatus showing the actuating shaft and the parts operated thereby. Fig. 4 is a perspective view of one form of type holder, which 30 we use in connection with the movable type bars. Fig. 5 is a detail perspective view of a different form of detachable holding means for a movable doll or figure. Fig. 6 is a view similar to Fig. 3 showing a spring 35 motor for operating the mechanism.

40 The object of our invention is to produce a typewriting doll toy comprising among its members a part constructed to simulate a typewriting machine, and preferably supported upon a part constructed to give the appearance of a typewriter desk or stand, in conjunction with a figure, the arms of which extend over the key board portion of the typewriter part, and are operated in any 45 desired manner so as to appear to be operating the typewriter keys.

50 We also contemplate providing one or more movable type bars, and a paper support ordinarily in the form of a roller; and

means for inking the type bars, which conveniently consist of a narrow typewriter ribbon supported on spools and guided between the type and the paper support, suitable connections being provided from the actuating mechanism to the various parts, so that as 55 the arms of the doll or figure are actuated the type bars will be actuated to print letters or words on a sheet of paper, which may also be fed by suitable feeding mechanism operatively connected with the actuating 60 shaft for rotating the feed roll.

We also contemplate providing means for changing the type so that different words or letters can be printed, and we also contemplate supporting the doll or figure detachably with respect to the apparatus so that its arms can be disconnected from the arm actuating devices, and the doll removed from the apparatus, if desired.

We also contemplate providing the doll 75 supporting means with mechanism for supporting any ordinary doll of the appropriate size having movable arms, the arms of the doll or figure being provided with clips to engage the arm operating devices so that the 80 device may be put on the market without the doll or figure if desired and used with any ordinary doll of the appropriate size having movable arms.

Our invention also comprises the novel 85 features of construction and operation hereinafter fully described.

In the accompanying drawings we have shown the preferred embodiment of our invention together with certain modifications 90 thereof, but we do not desire to be limited to the specific embodiment herein shown nor to the details of construction herein shown, the scope of the invention being defined in the appended claims.

95 In the embodiment shown herein and selected by us for purposes of illustration 1 represents a part constructed to simulate the appearance of a typewriting machine and preferably having combined therewith a 100 supporting part formed to represent a typewriting desk or stand upon which the machine is mounted, as indicated at 2. These parts will ordinarily be constructed of wood, or tin, or other sheet metal, or any 105 other preferred material, and it is only necessary that these parts shall have the outward appearance of a typewriter and stand,

the detail parts of which may be indicated in various ways, more or less realistically as preferred. For example, we ordinarily indicate the key-board by painting circular portions to indicate the keys upon a flat surface, corresponding with the key-board portion of the typewriting machine, as indicated at 3, and the drawers of the desk may be painted on the exterior of the front face. At the same time, more elaborate and expensive embodiments of the device may represent these parts more realistically than above stated.

4 represents a support for the doll or figure which will ordinarily simulate the appearance of a chair, and 5 represents the doll or figure provided with movable arms 6, which extend over the key-board portion 3. The doll may be made integral with or secured to other parts of the apparatus, and the arms may be actuated in any desired manner, within the scope of our invention, but we prefer to have the doll or figure detachable, and to operate the arms by means of vertically movable arm operating devices or rods, 7, extending upwardly through apertures in the key-board part, 3, and having their lower ends connected to actuating cranks, 8—8, upon a crank shaft, 9, extending through the body of the apparatus, for actuating the devices 7, the actuating shaft 9 being rotated in any convenient manner, as for example, by a crank, 10, although it may be operated by a spring motor or other motor, as hereinafter described. In this instance, the back of the chair or doll support, 4, is provided with means for detachably securing the body of the doll or figure thereto. In Figs. 1 and 2 for example, this comprises a fork shaped clip, 11, secured to the back of the support, 4, and adapted to engage a headed button, 12, conveniently located at the back of the doll or figure, for example at the waist line, and a similar clip, 13, is conveniently secured to each of the hand portions of the movable arms of the doll so as to be capable of detachably securing said arms to the arm operating devices, 7, which are in this instance, provided with enlarged head portions, 14. One of the clips, 13, is shown detached in Fig. 2^a. By the means just described it will be apparent that the doll or figure can be detached from the device and used like any ordinary doll or figure, and it will also be apparent that any ordinary doll of the required size, having movable arms, could be provided with the button, 12, and the clips, 13, which may be furnished with the apparatus in case it is supplied to the trade without the doll or figures.

In Fig. 5 we have shown different means for supporting the doll on the chair or support, 4, which consists of a pair of spring arms, 15, secured to the back of the support

here indicated by 4^a, and adapted to embrace the waist portion of the doll or figure and hold it firmly in position so that any ordinary doll may be held in fixed relation with the support without the necessity of using the button, 12. It is not essential to our invention that the simulated typewriting machine should be actually capable of printing, but our invention contemplates the provision of means whereby this may be accomplished. Thus we have shown the apparatus provided with a pair of vertically disposed type bars, 16—16, of which there may be one or more, these bars being, in this instance, formed of spring material, and fastened to a cross bar, 17, at the base of the frame, and we prefer to provide the upper ends of these type bars with removable type. For example, in Fig. 1, we have shown the upper ends of the bars as shouldered and provided with reduced shanks passing through apertures in detachable type blocks, 18, on the faces of which may be letters or words, as for example, "Mamma" and "Papa".

In Fig. 4 a modification of this arrangement is shown in which the type bar indicated at 16^a has its upper end provided with a rectangular type holder, 18^a, into which a metallic block carrying the printing type or letters may be dropped, the front wall of the carrier, 18^a, being cut away to permit the type to project. The type bars are adapted to be guided from the actuating shaft, 9, in any desired manner, and in this instance, we have shown each type bar provided with a bracket portion, 19, arranged in line with one of the crank portions, 8—8, of the crank, 9, so that the said type bars will be alternately actuated during each rotation of the shaft. The type may be inked in any desired way, but we prefer to provide a narrow typewriter ribbon for this purpose, indicated at 20 and carried upon spools, 21—21, mounted on studs, 22—22, on opposite sides of the typewriting machine part. In this instance therefore the type will strike the ribbon and press it against the paper in making the impressions in a manner similar to the operation of an ordinary typewriting machine. The ribbon spools can be shifted by hand from time to time to bring fresh portions of the ribbon opposite the type.

The typewriting machine part is preferably provided with a paper support which will conveniently be in the form of a roller, 23, as shown, and the machine portion will be provided with strips of metal indicated at 24 for guiding a sheet of paper around the roller and holding it in contact therewith, and also with strips or guides, 25, for guiding the ribbon, 20, in front of the type and holding it out of contact with the paper. I also prefer to provide feed mechanism for feeding the paper, in this instance, consist-

ing of a ratchet wheel, 26, on the roller shaft, and an operating rod, 27, connected with a crank, 28, on the shaft, 9, and having a pawl or tooth, 29, engaging the ratchet wheel, 26, for moving the roller one tooth at each revolution of the actuating shaft, 9.

We also prefer to provide mechanism for simulating the tapping or clicking noise of a typewriting machine, and also means for operating a bell each time the paper roller is fed, although these accessories are not essential. In Figs. 2 and 3 we have shown a bell, 30, which is supported on the interior of the body of the machine, and provided with a spring hammer arm, 31, pivoted to the body of the device and provided with a trip arm, 32, which is in this instance arranged in the path of the crank, 28. The hammer arm is supported normally by a stop pin, 33, so as to be just out of contact with the bell. When the crank engages the trip arm, 32, the hammer arm will be elevated, and when the crank releases the trip arm the hammer arm will fall and cause the hammer to strike the bell.

We have also provided, as shown in Fig. 3, a device for producing a clicking sound which comprises, in this instance, a tooth wheel or ratchet wheel, 34, on the actuating shaft, 9, in operative relation with a spring pawl or tappet, 35, so that as the shaft is rotated a clicking sound will be produced by the pawl passing from one tooth to another. It will be obvious that a child may derive a great deal of amusement and interest by placing a sheet of paper around the supporting roller, 23, and operating the device so as to cause it to print letters or words on the paper, as the arms of the doll or figure are raised and lowered over the key board, to the accompaniment of a clicking sound, and the ringing of the bell, and the forward feed of the paper, all of which is readily accomplished by the mechanism described.

As before stated the doll may be a fixture in the device, and may be made of wood, tin, or other metal, or of any suitable material, but preferably the doll will be an ordinary doll of the required size to be in proportion with the apparatus, and will be detachably connected as previously described. Or the apparatus may be made up and sold without the doll or figure, and so constructed that any doll or figure of the appropriate size, having movable arms, can be readily secured in operative relation therewith.

It is not necessary that the moving parts of the mechanism should be operated by hand. In some instances, it may be desirable to have them actuated by a clock-work motor, or of some other form of motor, and in Fig. 6, for example, we have indicated a form of the apparatus in which a clock-work motor is connected with the actuating shaft there indicated at 9^a, clock-work being

indicated at 40, and provided with winding mechanism, 41, and starting and stopping lever, 42.

The apparatus may be made in any size desired from a small toy to a larger size and the device may also be used for advertising or other purposes.

What we claim and desire to secure by Letters Patent is:

1. In a typewriting doll toy, the combination with a part constructed to simulate a typewriting machine, of movable arm operating devices, means for connecting the arms of a doll thereto, a support for a doll, and actuating means for said arms operating devices.

2. In a typewriting doll toy, the combination with a part constructed to simulate a typewriting machine, of movable arm operating devices, means for connecting the arms of a doll thereto, a support for a doll, mechanism for producing a clicking sound, and actuating means for said arm operating devices and said sound producing mechanism.

3. In a typewriting doll toy, the combination with a part constructed to simulate a typewriting machine, a figure provided with movable arms extending over the key-board portion of the machine, actuating mechanism, and connections from said actuating mechanism to the said movable arms.

4. In a typewriting doll toy, the combination with a part constructed to simulate a typewriting machine, a figure provided with movable arms extending over the key-board portion of the machine, mechanism for producing a clicking sound, actuating mechanism, and connections from said actuating mechanism to said movable arms and to said sound producing mechanism.

5. In a typewriting doll toy, the combination with a part constructed to simulate a typewriting machine, of vertically movable arm operating devices having portions extending above the key-board portion thereof and provided with means for connecting the arms of a doll thereto, a support for a doll, and actuating means for said arm operating devices.

6. In a typewriting doll toy, the combination with a part constructed to simulate a typewriting machine, of vertically movable arm operating devices having portions extending above the key-board portion thereof and provided with means for connecting the arms of a doll thereto, a doll supported adjacent to said typewriter part, and provided with movable arms, connected to said arm operating devices, and actuating means for said arm operating devices.

7. In a typewriting doll toy, the combination with a part constructed to simulate a typewriting machine, of vertically movable arm operating devices having portions extending above the key-board portion thereof,

and provided with means for detachably connecting the arms of a doll thereto, a support for a doll adjacent to said typewriter part, and actuating means for said arm operating devices.

8. In a typewriting doll toy, the combination with a part constructed to simulate a typewriting machine, of vertically movable arm operating devices having portions extending above the key-board portion thereof, and provided with means for detachably connecting the arms of a doll thereto, a support for a doll adjacent to said typewriter part, means for detachably securing a doll to said support, and actuating means for said arm operating devices.

9. In a typewriting doll toy, the combination with a part constructed to simulate a typewriting machine, and provided with a paper support, and a movable type bar, of movable arm operating devices, provided with means for connecting the arms of a doll thereto, a support for a doll, and actuating means operatively connected with said type bars and with said arm operating devices.

10. In a typewriting doll toy, the combination with means for supporting and feeding a sheet of paper, a movable type bar, movable arm operating devices provided with means for connecting them with the arms of a doll, a support for a doll, and actuating means operatively connected with said paper feeding mechanism, said type bar, and said arm operating devices.

11. In a typewriting doll toy, the combination with means for supporting and feeding a sheet of paper, a movable type bar, movable arm operating devices provided with means for connecting them with the arms of a doll, a support for a doll, mechanism for producing a clicking sound and actuating means operatively connected with the paper feeding mechanism, type bar and arm operating devices, and said sound producing mechanism.

12. In a typewriting doll toy, the combination with a part constructed to simulate a typewriting machine, and provided with a paper support, a movable type bar having means for detachably holding a printing type, and a removable type carried thereby, of movable arm operating devices provided with means for engaging the movable arms of a doll, a support for a doll, and actuating means operatively connected with said type bar, and with said arm operating devices.

13. In a typewriting doll toy, the combination with a part constructed to simulate a typewriting machine, and provided with a paper support and printing mechanism including a movable type bar, a figure having movable arms extended above the key-board portion of said typewriting machine part, operating devices for moving said arms ver-

tically, and actuating means operatively connected to said printing mechanism and to said arm operating devices.

14. In a typewriting doll toy, the combination with a part constructed to simulate a typewriting machine, and provided with means for supporting and feeding a sheet of paper, and printing mechanism including a movable type bar, of a figure having movable arms extended above the key-board portion of said typewriting machine part, operating devices for moving said arms vertically, a motor and operative connections between said motor and said paper feeding, printing and arm operating mechanism. 80

15. In a typewriting doll toy, the combination with a part constructed to simulate a typewriting machine, and provided with a paper supporting roller, feed mechanism therefor, a movable type bar, and means for supporting an inking ribbon, of vertically movable arm operating devices extending above the key-board portion of the typewriting machine part, and provided with means for connecting them to the movable arms of a doll, and an actuating shaft provided with cranks operatively connected with said arm operating devices, and in operative relation with said type bar, and connections between said shaft and the paper feed mechanism. 95

16. In a typewriting doll, the combination with a part constructed to simulate a typewriting machine, having the keyboard portion provided with a pair of apertures, 100 and provided with a paper supporting roll, a plurality of movable type bars, and feed mechanism for the paper roll, of vertically movable arm operating devices extending through said key-board apertures, and provided with means for connecting them with the movable arms of a doll, a doll support, an actuating shaft provided with cranks connected with said arm operating devices, said type bars having portions adapted to 110 be engaged by said cranks to operate the type bars, and connections between said shaft and the paper feed mechanism. 105

17. In a typewriting doll the combination with a part constructed to simulate a typewriting machine, having the key-board portion provided with a pair of apertures, and provided with a paper supporting roll, a plurality of movable type bars, and feed mechanism for the paper roll, of vertically 115 movable arm operating devices extending through said key-board apertures, and provided with means for connecting them with the movable arms of a doll, a doll support, an actuating shaft provided with cranks 120 connected with said arm operating devices, said type bars having portions adapted to be engaged by said cranks to operate the type bars, a toothed wheel on said shaft, a spring pawl for engaging said wheel to pro- 130

duce a clicking sound, and connections between said shaft and the feed mechanism.

18. In a typewriting doll toy the combination with a part constructed to simulate a typewriting machine, of means for supporting and feeding a sheet of paper, printing means for printing characters on the paper, movable arm operating devices means for connecting them with the arms of a doll, a

support for a doll, and actuating means operatively connected with said paper feeding and printing mechanism and with said arm operating devices.

In testimony whereof we affix our signatures.

MONROE M. SCHWARZSCHILD.
BELLE SCHEUER.
